UNITED STATES PATENT OFFICE.

NICHOLAS S. VEDDER, OF TROY, AND TOBIAS S. HEISTER, OF LANSINGBURG,
ASSIGNORS TO NICHOLAS S. VEDDER, OF TROY, NEW YORK.

DESIGN FOR FRANKLIN STOVE.

Specification forming part of Design No. 7,997, dated January 12, 1875; application filed December 30, 1874.
[Term of Patent 3½ years.]

To all whom it may concern:

Be it known that we, NICHOLAS S. VEDDER, of the city of Troy, in the county of Rensselaer and State of New York, and TOBIAS S. HEISTER, of Lansingburg, in said county of Rensselaer, New York, have jointly invented and produced a new and original ornamental Design for Franklin Stoves, of which the following is a specification, reference being had to the accompanying cut, print, or engraving of a stove having our said new design.

One part of this invention consists of the design for cap-plate A, composed of the central angular cornice b b, over the three-sided panel-tablet c, with ornamented ends, and surmounted by the spread crest d and side scrolls e e, and the end sections F F, formed by the ornamented walls g, central cap-pieces h, and lateral studs i, all shaped and arranged together so as to present substantially the same appearance as is represented in the aforesaid cut.

Another part consists of the design for the columns J J, composed of the plain outer borders k and the oblong rectangular panels l, ornamented by two series of ribbed bars, m and n, crossing each other diagonally, with a diamond-shaped ornament, o, on a lozenge-shaped base, p, upon a rhomb-shaped bed, q, at each intersection of the two series of ribs, m and n, and with the oblique cruciform recesses r between, all shaped and arranged as shown in the aforesaid print.

Another part consists of the design for the sliding doors S, composed of the panel-surface t, ornamented by two series of narrow ribs crossing each other, with intervening alternate quadrilateral flat and pyramidal surfaces, the semi-columns u along the sides, and the flat arch v over the top of the said ornamented panel-surface, and the surrounding ornamental border w, all shaped, ornamented,

and arranged together, substantially as represented in the aforesaid engraving.

Another part consists of the design for the leg X, composed of the side scrolls y y, semi-rosette z, pendent leaf a, side and ankle moldings f, and box-foot j, all shaped and combined as represented in the aforesaid print.

What we claim as our joint invention is—

1. The design for the cap-plate A, composed of the central cornice b b, tablet c, crest d, side scrolls e e, and sections F F, each formed by the wall g, lateral studs i i, and intermediate cap-piece h, all shaped, ornamented, and arranged together, substantially as shown and specified.

2. The design for the side columns J J, composed of the outer borders, k, and the panels l, ornamented by the series of ribbed crossing-bars m n, with the diamond ornaments o, lozenge bases p, and rhomb-shaped beds q, and the intervening oblique cruciform recesses r, all shaped and arranged together as represented in the aforesaid cut and above specified.

3. The design for the doors S, composed of the panel-surface t, ornamented as shown and described, the semi-columns u u, arch v, and surrounding ornamental border w, all shaped and combined as specified and shown.

4. The design for the leg X, composed of the side scrolls, y y, semi-rosette z, pendent leaf a, side moldings f, and box-foot j, all shaped and combined as shown and described.

In testimony whereof we hereunto subscribe our names this 24th day of December, 1874.

NICHOLAS S. VEDDER.
TOBIAS S. HEISTER.
